UNITED STATES PATENT OFFICE.

ACHILLE COLOMBO, OF TURIN, ITALY, AND THEODOR HUGO, OF WILMERSDORF, NEAR BERLIN, GERMANY, ASSIGNORS TO FIRM GEBRÜDER TELLSCHOW, OF BERLIN, GERMANY.

ENVELOP-MAKING MACHINE.

1,091,811.

Specification of Letters Patent. Patented Mar. 31, 1914.

Application filed January 17, 1913. Serial No. 742,575.

To all whom it may concern:

Be it known that we, ACHILLE COLOMBO, advocate, a subject of the King of Italy, residing at Via Arcivescovado 10, Turin, in the Kingdom of Italy, and THEODOR HUGO, engineer, a subject of the King of Prussia, residing at Aschaffenburgerstrasse 3, Wilmersdorf, near Berlin, in the German Empire, have invented new and useful Improvements in Envelop-Making Machines, of which the following is a specification.

In known rotary envelop making machines, there is a vertical main shaft carrying at its upper end gumming arms adapted to apply gum to the lower flap of an envelop blank and then, as the shaft revolves, to pass the blank to a folding device. According to the present invention such machines are so constructed that they first apply to the envelop blank a lining blank so that the folding device produces lined envelopes. The arrangement is such that the speed of the machine is not affected, so that it will have the same output for lined envelopes as the previous machines have for unlined envelopes; moreover, a second machine, which had formerly to be used for lining the cut blanks, is dispensed with.

The invention is illustrated in the accompanying drawings wherein—

Figure 1 is a plan of the machine and Fig. 2 a side elevation. Fig. 3 shows a lining blank, Fig. 4 an envelop blank and Fig. 5 shows the one blank superimposed on the other, in the position in which they are stuck together.

The machine operates as follows: As the vertical shaft *a*, carrying the arms *b'*, *b²*, *b³*, *b⁴* rotates in the direction of a clock hand, 40 the arm *b'* passes over a known gumming device *c* and after turning through 90° from the position shown, arrives above the cut lining blanks *d* which are stacked on an adjustable table. The arm is then lowered 45 upon the pile of blanks *d* so that it leaves a narrow strip of gum *d²* on the lower flap *d'* (Figs. 1 and 3). Since the under surface of the gummer, which is covered with gum, is wider than the strip *d²*, that part of the 50 gummer which does not come into contact with the lining blank *d* retains its gum and this is applied as hereinafter described, to the lower flap *e'* of the envelop proper. When the gumming arm is raised again the 55 top blank *d* adheres thereto and is carried

by the arm as the latter turns through another angle of 90° to a position above the pile of envelop blanks. Here the arm is lowered and the lining blank is deposited on the top envelop blank *e*, the relative position of the two being that shown in Figs. 1 and 5; the periphery of the lining blank lies within that of the envelop blank. At the same time as the lining blank is laid on the envelop blank *e* the outer edge of the lower flap *e'* of the latter is gummed (see *e²*, Fig. 5) by the gummer. Before the gumming arm moved from its last position into the present position, a separate gummer *f* applied a strip of gum *e³* (Fig. 4) to the lower flap *e'* of the envelop blank *e*, so that when the arm placed the lining blank on the envelop blank, the two were stuck together by the gum *e³*. In order to insure this a pressing plate *g*, *g* descends upon the lining blank after this has been brought into position by the arm, and presses the blank upon the top envelop blank *e*. As the arm turns further to the folding mechanism it takes with it both the envelop blank *e* and the lining blank *d*, the former by the surface *e²* and the latter by the surface *d²* since both blanks adhere to the gummer by these surfaces, and the two blanks *d* and *e* are stuck together by the gum *e³*. At the folding mechanism the 75 lined envelop blank is folded to form an envelop in the usual manner. If it is desired to make envelopes having a gummed top flap, this flap *m* of the envelop blank *e* is gummed when the arm is in the position *b³* by a separate gummer *h* moving to and fro. When the gumming arm has arrived at the position *b⁴* and has delivered the lined blank to the folding mechanism, it continues its movement and the same operations are repeated. All four arms of the machine come into action in succession and they are turned by the main shaft *a*. The arms are raised and lowered by suitable devices, the construction shown being as follows: Upon 100 shaft *a* is mounted a spider *i* having radial arms *j* that correspond in number to the number of arms *b'*, *b²*, etc., and carry rollers *k*. These rollers are consecutively engaged by a worm *m* which is so contoured as to impart the desired intermittent movement to the shaft. In order to raise and lower the arms *b'*, *b²*, etc., there is provided a cam *n* that engages a cam roller *o* of lever *p*, fulcrumed at *q*, and secured by link *r* to a plun- 110

ger s. When this plunger is raised by the cam, it will raise the arm, while upon the lowering of the plunger, the arm will descend by gravity.

5 We claim:

1. A machine for making lined envelopes, comprising a gum carrier, adapted to engage an envelop lining while projecting with its gummed section partly therebeyond, and means for advancing said carrier together with the lining over an envelop blank to cause an engagement of its projecting gummed section with the blank-flap.

10 2. A machine for making lined envelopes comprising a vertically reciprocable gum carrier adapted to engage an envelop lining

while projecting with its gummed section partly therebeyond, means for applying an adhesive to the body of an envelop blank, means for intermittently advancing the gum 20 carrier together with the lining so as to carry the lining into engagement with the gummed body of the blank, while the projecting part of the carrier is simultaneously brought into engagement with the blank- 25 flap.

ACHILLE COLOMBO.
THEODOR HUGO.
